Primary Examiner — Lakiya G Rogers*Assistant Examiner* — Altaira J Swangin(74) *Attorney, Agent, or Firm* — DWC Law Firm, P.S.; David Chen(57) **CLAIM**

The ornamental design for a headlamp, as shown and described.

DESCRIPTION

FIG. 1 is a top perspective view of a headlamp according to the present disclosure.

FIG. 2 is a bottom perspective view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a top perspective view thereof showing a head strap to which the headlamp can be attached.

The broken lines form no part of the claimed design. The even broken lines show portions of the headlamp which form no part of the claim. The uneven broken lines show boundaries which form no part of the claim. In FIGS. 1-3, the unshaded region immediately outside of the uneven broken lines, bounded by the circular perimeter, is a part of the claimed design.
